SLIPPER

Donna L. Fenlason, New York, N. Y.

Application October 20, 1951, Serial No. 17,049

Term of patent 14 years

(Cl. D7—7)

To all whom it may concern:

Be it known, that I, Donna L. Fenlason, a citizen of the United States, residing at the city of New York, Borough of Manhattan, county of New York and State of New York, have invented a new, original, and ornamental Design for a Slipper, of which the following is a specification, reference being had to the accompanying drawing, forming a part thereof, wherein

Fig. 1 is a plan view of a slipper, showing my new design; and

Fig. 2 is a perspective view thereof.

I claim:

The ornamental design for a slipper, substantially as shown.

DONNA L. FENLASON.
